THE NATIONAL LITHOGRAPHING COMPANY,
WASHINGTON, D. C.

UNITED STATES PATENT OFFICE.

CHARLES L. KUEHN, OF ST. LOUIS, MISSOURI.

ADJUSTABLE RACK FOR STRETCHING LACE CURTAINS, &c.

SPECIFICATION forming part of Letters Patent No. 520,690, dated May 29, 1894.

Application filed September 4, 1893. Serial No. 484,716. (No model.)

To all whom it may concern:

Be it known that I, CHARLES L. KUEHN, of St. Louis, State of Missouri, have invented certain new and useful Improvements in Adjustable Racks for Stretching Lace Curtains and Similar Articles, of which the following is a full, clear, and exact description, reference being had to the accompanying drawings, forming a part hereof.

10 My invention relates to an improved adjustable rack for stretching lace curtains and similar articles, and consists in the novel construction, combination and arrangement of parts as will be more fully described and designated in the claims.

In the drawings: Figure 1 is a perspective view of my complete rack, showing the same ready for use. Fig. 2 is an enlarged vertical cross-section of Fig. 1. Fig. 3 is an enlarged 20 side elevation of one of the end posts with parts broken away, showing the connection of the horizontal bars. Fig. 4 is an enlarged detail perspective more clearly showing a detachable pad, which I use in carrying out my 25 invention.

1 indicates an adjustable rack, which is constructed of two vertical posts 2 and 3, which are provided with supports 4 at their lower ends. These posts being exactly the same in 30 construction, I will describe but one. The post is constructed with two vertical parallel bars 5 and 6, which are held a suitable distance apart by blocks 7, 8 and 9 being placed between them, and held in position by bolts 35 10, or any well known means. The block 7 is located at the top, and the blocks 8 and 9 are located adjacent the bottom of said bars. These posts are connected to the supports 4 and provided with braces 11. The block 9 is 40 located a suitable distance above the block 8, which forms an opening between said blocks. Located in this opening is one end of a horizontal bar 12, the opposite end being located in the other post in the same manner. The 45 upper end of the block 8 is cut at an angle. The end 13 of the horizontal bar 12 is formed on its lower edge with a notch 14, which engages the angle end of the block 8 so when a wedge 15 is driven in between the block 9 50 and the top of the end 13 it will rigidly connect the horizontal bar 12 with the posts 3. (See Fig. 3 for illustration.) The horizontal

bar 12 is constructed with two parallel bars 16 and 17 and the end 13 of the bar 12 is placed between these bars 16 and 17, and held in position by bolts 18. 19 indicates a horizontal bar which is constructed of two parallel bars 20 and 21, they being connected together at their ends by a short bar 22 being located between them, and held in position by bolts 23, 60 the short bars 22 projecting a suitable distance beyond the ends of the bars 20 and 21 to allow them to be placed between the bars 5 and 6 of the posts 2 and 3, one end of each of said bars engaging each post, and held in 65 position by pins 24 passing through apertures 25 formed in the bars 5 and 6 of the posts, and apertures formed in the adjacent end of the bar 22 the apertures in one bar being in alignment with the apertures in the adjacent 70 bar. By the construction of these apertures, the bar 19 can be vertically adjusted in the posts.

The bars 16 and 17, which form the horizontal bars 12, are provided with a suitable 75 number of apertures 26 and the bars 20 and 21, which form the bars 19, are also provided with a like number of apertures 27, these apertures in the adjacent bars being in alignment with each other. 80

28 indicates a vertical bar which is horizontally adjustably mounted in the bars 19 and 12. The lower end of said bar is provided with an aperture and a pin 29 is passed through an aperture 26 in the bar 12 and 85 through an aperture in the lower end of said bar which holds said end in position. A pin 30 is passed through an aperture in the bar 19 and through an aperture in the upper end of the bar 28, which holds the upper end of 90 said bar in position. The upper end of the bar 28 is provided with a series of apertures 31.

32 indicates pads which are connected to each side of the posts 2 and 3, as shown in Figs. 1, 2, and 3 and held in position by being 95 tacked along each side and at their ends. These pads extend from the top of the brace 11 to the top of said posts.

33 indicates pads which are connected to the bar 19, as shown in Figs. 1, 2 and 3 and 100 extend the entire length of said bar, they being connected to said bar by the same means as the pads 32 are connected to the posts.

The bar 12 is provided with pads 34 located

on said bar in the position shown in Figs. 1, 2 and 3 and connected to said bar by the same means as are used with the pads 33.

Connected to each side of the vertical bar 28 and extending upward a suitable distance from the bar 12 are short bars 35. These bars are to enlarge the bar 28 so that its sides will be in alignment with the sides of the bar 12. Connected to one side of each of these bars 35 is a pad 36, which is connected to the bar by the same means as the pads 34 are connected to the bar 12. Detachably connected to the upper end of the vertical bar 28, as shown in Fig. 1, are two bars 37 and 38. These bars are hinged together at one edge by a piece of canvas 39, or like material, the canvas being wide enough so that the bars 37 and 38 can be separated so they will engage the opposite side of the bar 28, they being held in position after being placed on the bar 28 by a hook 40 connected to the bar 37 and engaging an eye 41, which is connected to the adjacent edge of the bar 38. The parts 44 and 45 are in every way similarly constructed, as are the bars 37 and 38, but are shorter and of differing lengths; their purposes will be hereinafter shown. Connected to these bars 37 and 38, as shown in Fig. 4, are pads 42. These pads all being the same in construction, I will now proceed to describe one of them.

A piece of canvas, or like material, is cut in strips of the desired width and length. After one edge is tacked in the required position a suitable amount of hair, cotton, or any suitable material is placed beneath the canvas and the opposite edge is tacked down over the cotton or hair in position, thus making a very convenient pad for a purpose hereinafter mentioned. These pads are constructed with a suitable number of stripes 43. These stripes being of different color than the body of the pads and are parallel with the edges of said pads. By these stripes a person pinning a curtain on will be guided, and thus be able to get the curtain straighter than they would were the stripes omitted.

The operation is as follows: After curtains have been laundered and it is desired to place them on the rack for drying, the operator first removes the pin 29 and 30 and slips the vertical bar adjacent one end of said rack and removes the bars 37 and 38 by disengaging the hook 40. When this is done the horizontal bar 19 can be adjusted vertically by removing the pins 24 which will allow said bar to be so adjusted. When it has been adjusted to the required size, the operator pins one side of the curtain to the pad 33 which is carried by the bar 19, and the opposite side of said curtain to the pad 34 carried by the hori-

zontal bar 12. After the sides have been securely pinned, the operator pins one end of said curtain to the pad 32 carried by the post 2. When this is done the operator moves the vertical bar up adjacent the free end of the curtain and places bars such as 44 or 45, whichever may be the desired length, on the bar 28. When they are in place their position will be the same as the bars 37 and 38. After this is done the operator pins the loose end of the curtain to the pads carried by the bar 28. After the curtain has been securely pinned to the pads as stated, the operator can stretch the curtain the required size by raising the bar 19 up and moving the bar 28 outward from said curtain. The bar 19 can be readily held in position at any point by the pins 24, and the bar 28 can be held at any convenient point by the pins 29 and 30.

By the construction herein described, the rack can be readily and quickly adjusted to fit curtains of different sizes.

Two curtains of the same size can be dried on the rack at the same time, one being placed on each side of said rack in the manner hereinbefore described.

When it is desired to ship or store the rack, it can readily be taken apart by removing the wedges 15 which will allow the end blocks 13 of the bar 12 to be removed from the posts 2 and 3. When this is done the rack can be placed in a very compact position, thus making it very convenient for shipping or storing.

What I claim is—

1. An adjustable rack for drying curtains, constructed of two vertical posts, two horizontal parallel bars mounted in said posts, a vertical bar mounted in said horizontal bars, and pads of the class described in combination with said posts and bars, said pads constructed with stripes parallel with their sides, substantially as set forth.

2. An adjustable rack constructed with two vertical posts, a horizontal bar 12 detachably located in the lower ends of said posts, a horizontal bar 19 vertically adjustably located in the upper end of said posts, a vertical bar 28 horizontally adjustably located in the bars 12 and 19, detachable bars 37 and 38 carrying pads 42, said bars being hinged together and detachably connected to the bar 28 by a hook 40 connected to the bar 37 and engaging an eye 41 connected to the adjacent edge of the bar 38, substantially as set forth.

In testimony whereof I affix my signature in presence of two witnesses.

CHARLES L. KUEHN.
